United States Patent

Des. 240,841
Patented Aug. 3, 1976

240,841

GOLF CLUB

Karsten Solheim, 501 Wakonda Lane,
Phoenix, Ariz. 85023

Filed Jan. 31, 1974, Ser. No. 438,299

Term of patent 14 years

Int. Cl. D21—02

U.S. Cl. D34—5 GC

FIG. 7.

FIG. 8.

FIG. 9.

FIG. 10.

FIG. 11.

FIG. 12.

FIG. 1 is a front view in perspective of a golf club embodying my new design.

FIG. 2 is a fragmentary front view in perspective of the golf club shown in FIG. 1.

FIG. 3 is a fragmentary rear elevation of the golf club shown in FIG. 1.

FIG. 4 is a sectional view of the fragmentary golf club shown in FIG. 1 taken along a line 4—4 shown in FIG. 3.

FIG. 5 is a fragmentary end elevation of the golf club shown in FIG. 1.

FIG. 6 is a top fragmentary view of the golf club shown in FIG. 1.

FIG. 7 is a fragmentary rear elevation of another embodiment of my new design.

FIG. 8 is a fragmentary end elevation of the golf club shown in FIG. 7.

FIG. 9 is a fragmentary rear elevation of another embodiment of my new design.

FIG. 10 is a fragmentary end elevation of the golf club shown in FIG. 9.

FIG. 11 is a fragmentary rear elevation of yet another embodiment of my new design.

FIG. 12 is a fragmentary end elevation of the golf club shown in FIG. 11.

My new design may be applied to clubs that have a different loft and lie in a conventional manner.

I claim:

The ornamental design for a golf club, substantially as shown and described.
